SUCTION CLEANER

Filed April 5, 1947

UNITED STATES PATENT OFFICE

2,581,974

SUCTION CLEANER

Donald G. Smellie, Canton, Ohio, assignor to The Hoover Company, North Canton, Ohio, a corporation of Ohio

Application April 5, 1947, Serial No. 739,593

5 Claims. (Cl. 183—58)

1

The present invention relates to suction cleaners in general and more particularly to new and improved filter-shaking mechanism which provides a storage support for the cleaner and is normally maintained in an inoperative filter-shaking position.

An object of the invention is to provide a new and improved suction cleaner having a filter-shaking mechanism. Another object is to provide a filter-shaking mechanism which forms a support for storing the cleaner. A further object is to provide a suction cleaner having means to support the operator while actuating the filter-shaking mechanism. Another object is to provide a filter-shaking mechanism which is normally locked to prevent accidental operation thereof and provide a storage support for the cleaner. Still another object is to provide a filter-shaking mechanism which is controlled by the removable-attachment of a cover for the cleaner casing. And still another object is to provide a filter-shaking mechanism which forms a latch for attaching a cover to the cleaner casing. Other objects and advantages of the invention will be apparent from the following specification and drawings, wherein:

Figure 1 is a longitudinal vertical section, partly in elevation, of one embodiment of the invention;

Figure 2 is a top plan view of part of the filter-shaking mechanism;

Figure 3 is an elevational view of the cleaner in storage position.

The embodiment of the invention herein disclosed comprises an elongated casing 10 closed at its exhaust end by a cap 11 having an outlet opening 12, and the suction end of the casing is closed by a cap 13 provided with an inlet opening 14. Each of the openings 12 and 14 are adapted to receive one end of an unshown hose which is provided at its opposite end with a surface cleaning tool in a manner well known in the art. The casing is supported on a pair of runners 15 to enable the operator to pull the cleaner over the supporting surface by means of a force exerted through the unshown hose attached to either of the end caps 11 or 13. Provided at the top of the cleaner casing 10 is a handle 16.

Within the casing 10 is a motor-fan unit 17 of conventional design and which is supported at its forward end by a resilient rubber ring 18 carried by a fixed bulkhead 19 mounted in the casing 10. A final filter 20 is supported on the bulkhead 19 at the intake to the fan chamber

2

of the motor-fan unit 17. The rear end of the motor-fan unit is supported in a resilient ring 21 carried by a rear bulkhead 22 fixedly secured to the casing 10 by a plurality of screws 23.

Arranged between the bulkhead 19 and the suction end cap 13 is a dirt-filtering bag 25 having a cylindrical wall 26 and a closed end wall 27, while the open end of the bag is secured to an annular flange 28 projecting inwardly from an end wall 29 which is secured to the casing, and the annular flange 28 defines an opening 30 to the filter bag 25. The bag opening 30 is closed by the end cap 13 which is removably-attached to the casing 10 by a lip 31 on the end cap seating in a bracket 32 mounted on the casing, and a latch 33 secured to the casing 10 cooperates with the end cap 13 to force the latter against the end wall 29 of the casing 10 while a seal 34 prevents leakage of air therebetween.

The end wall 27 of the filter bag is supported on a circular frame 36 secured to a substantially U-shaped bracket 37 terminating in arms 38 and 39 extending along the cylindrical wall 26 of the bag 25. A U-shaped lever 40 has its arms 41 and 42 pivotally supported at their lower ends on a rod 43 mounted in a frame 44 secured to the casing 10, and the arms 41 and 42 are respectively pivoted at their upper ends to the bracket arms 38 and 39. A link 45 is pivotally connected to the bracket arm 39 and the frame 44 and is the same length as lever arm 42 so that upon pivotal movement of the lever 40 the end wall 27 of the bag 25 will at all times move in a plane parallel to the casing front wall 29 and to the open end 30 of the bag. Arranged about the rod 43 are a pair of torsion springs 46 having one of their ends 47 resting against the frame 44 and their opposite ends 48 abut lugs 49 on the frame 44 to at all times urge the link 45, the lever arms 41 and 42 and the bracket 37 rearwardly within the casing 10 to draw the bag 25 taut.

The filter-shaking mechanism comprises a U-shaped connecting member 50, the opposite ends 51—51 of which are connected to the lever arms 41 and 42 and has its center portion 52 adapted to engage the vertical and inclined faces 53 and 54 of an engaging member 55. A torsion spring 60 is arranged about each pivoted end of the connecting member 50 and operates to at all times urge the center portion 52 of the member 50 into sliding engagement with the inclined surface 61 of a guide member 62.

The guide member 62 is disposed centrally below the filter bag 25 and has its inclined top

wall 61 merging into a flat wall 63 and is provided with a plurality of lugs 65 which are attached to the casing 10. A slot 66 is formed in the walls 61 and 63 for the reception of the engaging member 55 which is rigidly attached to a flat portion 67 of a rod 68 for actuating the bag shaking mechanism. A spring 70 is disposed about the rod 68 between a stationary wall 69 and a member 56 rigidly attached to the rod 68 and tends to at all times force the latter to the left as viewed in Figure 1. The bag shaking rod 68 is supported by the wall 69, bulkheads 19 and 22 and extends outwardly beyond the end cap 11 and terminates in a handle 72.

The end cap 11 is provided with a flat surface 73 and a recessed section 74 in which is received the projecting portion 75 of the plunger 68 and also the handle 72. It will be noted that the bag shaking handle 72 lies in the same plane as the flat surface 73 of the end cap 11 so that the handle 72 and the surface 73 of the end cap cooperate to provide a support for the cleaner when upended to the storage position shown in Figure 3. Formed in the end cap 11 is a handle 76 and a portion of the end cap is recessed at 77 to provide for the entrance of the operator's fingers to grasp the handle 76 and thus form a convenient handle for carrying the cleaner from place to place. In addition, the handle 76 acts as a support for the operator when the bag shaking rod 68 is manipulated by the handle 72.

In order to prevent inadvertent operation of the bag shaking mechanism and to form the latter into a rigid storage support for the cleaner, a locking means has been provided and includes a lever 78 pivotally mounted upon a U-shaped bracket 79 secured to the cleaner casing 10 adjacent to front end cap 13. One end 80 of the lever 78 is adapted to engage the end 81 of the bag shaking plunger 68, and the opposite end of the lever 78 is provided with an inclined surface 82 which engages a correspondingly inclined surface 83 formed on a member 84 integral with the suction end cap 13. A spring 85 mounted upon the lever 78 tends at all times to move the lever in a clockwise direction as viewed in Figure 1, so that when the end cap 13 is removed from the cleaner casing 10, the lever 78 moves out of engagement from the rod 68 whereby the latter may then be actuated to operate the bag shaking mechanism. When the end cap 13 is attached to the casing 10 the inclined surface 83 engages the surface 82 on the lever 78 to pivot the latter counter-clockwise and thus move the extreme end 80 against the end 81 of the bag shaking plunger 68 to thereby rigidly lock the latter in position.

When the suction cleaner is employed for normal surface cleaning, the motor-fan unit 17 draws the dirt-laden air through a suitable cleaning tool connected to inlet port 14 into the filter bag 25 which removes the dirt from the air, and the cleaned air passes outwardly through the walls of the bag and thence through the final filter 20. Thereafter the cleaned air enters the fan chamber and is exhausted through ports 86 in the rear bulkhead 22 and is discharged through the outlet 12 into the atmosphere.

During this normal surface cleaning operation, the end cap 13 is attached to the cleaner casing, and when so attached forces the locking lever 78 into engagement with the end 81 of the bag shaking plunger 68 to rigidly lock the latter so that it can not be actuated to operate the bag shaking mechanism. After the operator com-

pletes the desired surface cleaning, the cleaner can be upended into storage position as shown in Figure 3, and the cleaner is so supported by the flat area 73 on the end cap 11 and also by the handle 72 on the bag shaking plunger 68, and the latter is rigid with respect to the casing 10 since the locking lever 78 is abutting the bag shaking plunger 68.

When it is desired to remove the dirt accumulated in the filter bag 25 the suction end cap 13 is removed by manipulating the latch 33, and upon removal of the cap 13 the cam surfaces 82 and 83 are disengaged permitting the spring 85 to rotate the locking lever 78 clockwise as viewed in Figure 1 whereby the end 80 of the lever 78 is moved out of abutting relation with the end 81 of the bag shaking plunger 68, to permit the latter to be reciprocated. The cleaner casing is then upended into a filter cleaning position so that the end wall 29 lies flush upon a supporting surface which is preferably provided with a paper or the like for receiving the dirt to be removed from the bag 25.

To dislodge the dirt from the bag, the operator grasps the handle 72 and exerts a downward force thereon to move the engaging member 55 towards the front end wall 29 of the casing and cause the portion 52 of the connecting member 50 to slide along the inclined surface 61 and effect movement of the bag supporting arms 41, 42, the link 45 and the bracket 37 attached to the closed end wall 27 of the bag 25. As a result of movement of the member 55 the rear end wall 27 of the bag 25 is collapsed towards the front end of the cleaner casing against the force exerted by the torsion springs 46, and due to the arrangement of the arms 41 and 42 and the link 45 the rear end wall 27 of the bag is collapsed in planes which are parallel to the front end wall 29 of the cleaner casing. Upon continued movement of the engaging member 55, the portion 52 of the yoke 50 moves along the inclined ramp 61 until the surface 53 moves into the flat portion 63 of the guide member 62 whereby the portion 52 of the yoke 50 is disengaged from the engaging member 55 and thereafter the torsion springs 46 jerk the bag frame 31 and the end wall 27 of the bag back to their original position in which the bag is taut. This abrupt vibration of the bag effects the dislocation of the adhering foreign material which thereupon falls downwardly through the bag opening 30 in the casing end wall 29 onto the underlying supporting surface or the paper placed thereupon to receive the dislodged dirt. When the operator removes his hand from the handle 72 the spring 70 returns the handle 72 to bag shaking position, and the operator exerts another downward force upon the handle 72 and again collapses the bag to dislodge further dirt therefrom, and this operation is continued until the bag has been cleaned.

During reciprocation of the handle 72 the operator grasps the fixed handle 76 on the end cap 11 to support his weight and thus the handle 76 forms a support for the operator while he is actuating the bag shaking mechanism.

After the bag has been cleaned, the operator tilts the cleaner to its horizontal position and replaces the end cap 13, and as the end cap 13 is attached to the casing 10 the inclined surfaces 82 and 83 contact each other and cause the locking lever 78 to be pivoted counter-clockwise as viewed in Figure 1 to move the end 80 of the lever 78 against the end 81 of the bag shaking rod 68 to thereby rigidly lock the latter in position. When the bag shaking rod 68 is so

locked, the handle 72 and the flat surface 73 of the end cap 11 cooperate to provide a surface for supporting the cleaner in upended storage position as shown in Figure 3.

I claim:

1. A suction cleaner comprising a casing having a normally closed end and an open end, a removable cover for closing said open end, a filter in said casing communicating with said open end for removal of material dislodged from said filter, filter shaking means connected with said filter and including an operating handle disposed at said casing closed end, means movably mounting said handle on said casing for movement with respect to said closed end to actuate said filter shaking means, latch means for locking said operating handle with respect to said closed end in inoperative filter shaking position, support means at said closed end cooperating with said operating handle when in said locked inoperative position to form a support for supporting said casing thereon in upended cleaner storage position, and means for releasing said latch means and thus said operating handle for said movement of the latter to actuate said filter shaking means.

2. A suction cleaner according to claim 1 in which said latch means is controlled by removable attachment of said cover, said cover when attached locking said handle in its said inoperative position to support said casing in storage position and when removed releasing said latch means and thus said handle for said movement of the latter to actuate said filter shaking means.

3. A suction cleaner according to claim 1 in which said shaker operating handle is mounted on said casing for reciprocating movement in actuating said filter shaking means.

4. A suction cleaner comprising a casing having a normally closed end and an open end, a removable cover for closing said open end, a filter in said casing communicating with said open end for removal of material dislodged from said filter, filter shaking means connected with said filter and including an operating handle disposed at said casing closed end, means movably mounting said handle on said casing for

movement with respect to said closed end to actuate said filter shaking means, support means on said casing closed end for supporting said casing thereon in upended cleaner storage position, and means to position said operating handle in the plane of said support means to assist the latter in supporting said casing thereon in said cleaner storage position.

5. A suction cleaner comprising a casing having a normally closed end and an open end, a removable cover for closing said open end, a cleaner carrying handle rigidly mounted at said closed end, a filter in said casing communicating with said open end for removal of material dislodged from said filter, filter shaking means connected with said filter and including a movable operating handle disposed at said closed end adjacent said cleaner carrying handle when in inoperative position, means movably mounting said operating handle on said casing for movement with respect to said carrying handle to actuate said filter shaking means, and means connected with said filter shaking means to position said operating handle in said inoperative position adjacent said carrying handle to provide a support therewith for supporting the casing thereon in upended cleaner storage position.
